UNITED STATES PATENT OFFICE.

NICHOLAS HIRTZ, OF CINCINNATI, OHIO.

KNOCKDOWN UMBRELLA.

1,117,382.

Specification of Letters Patent.

Patented Nov. 17, 1914.

Application filed August 12, 1912. Serial No. 714,628.

To all whom it may concern:

Be it known that I, NICHOLAS HIRTZ, a citizen of the United States, residing at Cincinnati, in the county of Hamilton and State of Ohio, have invented certain new and useful Improvements in Knockdown Umbrellas, of which the following is a specification.

It is the object of my invention to provide a knockdown umbrella, the cover portion of which is arranged to fold with a plurality of cross-sectionally overlying folds so as to reduce the normal lengths of the ribs, and to arrange said folded cover portion along the median portion of the stick of the umbrella, both the ends of the stick being arranged to be detached for shortening said stick, the detached portions of the stick being capable of attachment alongside of the folded portion for forming a compact and short package.

The invention will be readily understood from the following description and claim, and from the drawings, in which latter:

Figure 1 represents an umbrella embodying my invention, partly broken away, and shown in spread relation. Fig. 2 is a side elevation of my improved device showing the umbrella in partly collapsed relation, a portion of the covering and part of the ribs being removed for better illustration of the parts. Fig. 3 is a similar view, showing the parts in collapsed relation, with the upper and handle sections of the stick removed. Fig. 4 is a side elevation of my improved device in completed knockdown relation. Fig. 5 is a longitudinal axial section, partly broken away, illustrating the pivotal connections and hinges and take-apart portions of my improved device. Fig. 6 is a bottom view of a detail partly in section and partly broken away, showing the rib-sleeve and one of the ribs pivoted thereon; and, Fig. 7 is a detail in side elevation showing the connection between the brace-sleeve and the rib-sleeve.

11 represents the stick of my improved device, which comprises a median section 12, an upper section 13, and a handle section 14. These sections are arranged to be connected and disconnected preferably by means of screw joints 15, 16.

17 represents the brace-sleeve, forming a slide, with which a catch 18 coöperates when the umbrella is in closed relation, the catch 18 being received in a slot 19 of the sleeve. The sleeve 17 has the braces 20 pivoted

thereon in a usual manner as at 21. A catch 22 coöperates with said brace-sleeve when the umbrella is in open relation, said catch being then received under said sleeve.

25 is a rib-sleeve which forms a slide, and is normally located at the upper portion of the stick. The rib-sleeve has the ribs 26 pivoted thereon in a usual manner, as at 27. The braces are pivoted to the ribs at 28. Each of the ribs has a hinge 31 therein between the rib-sleeve and the pivot 28, and a hinge 32 therein between the pivot 28 and the outer end of the rib, for forming inner rib-sections 33, median rib-sections 34, and outer rib-sections 35. The hinges 31 and 32 hinge in opposite directions when the umbrella is collapsed. The rib-sleeve 25 also has releasable connection with the upper section of the stick, instanced as a catch 37 received in a slot 38 in said sleeve, the upper end of the sleeve being received against a collar 39 secured to the upper section of the stick.

There is a releasable connection 40 between the sleeves, this connection being arranged to be released when the umbrella is in use as an umbrella and arranged to be connected for drawing the rib-sleeve with the brace-sleeve in the knockdown movement of the umbrella. I have shown this connection as a tube 41 which has threaded connection 42 with the brace-sleeve. The tube has hooks 43 at its upper end received in an annular slot 44 in the lower end of the rib-sleeve through recesses 45 in the lower wall of said slot. When the hooks are in said slot the rib-sleeve and brace-sleeve are connected for combined movement, and when said hooks are in line with said recesses said brace-sleeve has movement independent of said rib-sleeve. The catches 18, 22 and 37, are spring catches of the usual construction employed in umbrellas, the catches 18 and 22 being oppositely disposed on the median section of the stick, the catch 18 having its holding face presented downwardly and the catch 22 having its holding face presented upwardly. The catch 37 is located on the upper section of the stick.

The median and outer sections of the ribs are preferably U-shaped in cross-section, the inner sections thereof being preferably narrow in cross-section for being received partway in the channels of said median sections, and the links 46 of the hinges 32 are also preferably narrow in cross-section for

swinging readily in the channels of said median and outer sections of said ribs. Thimbles 47 are received across the hinges 31 and thimbles 48 are received across the 5 hinges 32 for stiffening the same when the umbrella is in use as an umbrella. The central portion of the cover 52 is fastened to the rib-sleeve, as shown at 53, and moves with said rib-sleeve. The outer edges of the 10 cover are fastened, as shown at 54, to the outer ends of the ribs.

When it is desired to collapse the umbrella, the umbrella having been first 15 opened for causing the hooks 43 to pass through the recesses 45, the tube 41 is turned for moving its hooks 43 into the annular slot 44 so as to place said hooks above the lower wall of said slot, thereby connecting the sleeves. The catches 22 and 37 20 being released, pulling the brace-sleeve 17 downwardly will draw the rib-sleeve 25 with it. The lower inner face of the rib-sleeve is beveled as shown at 55 to readily pass the catch 22. The inner ends of the 25 inner sections of the ribs and the central portion of the cover are thereby drawn toward the handle and the hinges 31 moved toward the stick. In this movement the inner sections of the ribs and the braces are 30 substantially parallel. The inner sections of the ribs are thereby laid lengthwise of the median section of the stick, with the inner stretch 56 of the cover between said stick and inner sections of the ribs. The 35 said inner sections and median sections of the ribs and the braces are by the same movement laid between the inner stretch 56 and the median stretch 57 of the cover. The hinges 31 are preferably nearer to the pivots 40 28 than to the pivots 27, so as to shorten the ultimate length of the knocked down umbrella. The outer sections 35 of the ribs are swung upon their hinges 32 for laying

said outer sections lengthwise of the stick, with the median stretch 57 and the outer 45 stretch 58 of the cover between the median and outer sections of the ribs. When the ribs, braces and cover of the umbrella have been collapsed, the upper and handle sections of the stick are released from the median section of the stick, and placed alongside of said median section of the collapsed umbrella, whereupon the collapsed portions will be suitably secured together, as by 50 straps 59.

Having thus fully described my invention, what I claim as new and desire to secure by Letters Patent, is:

In an umbrella, the combination with the stick, of a rib-sleeve and a brace-sleeve, each 60 of said sleeves having slidable connection with said stick, and a tube received about said stick between said sleeves, the lower end of said tube having threaded connection with said brace-sleeve and rotatable on said 65 brace-sleeve, the upper end of said tube provided with hooks, said rib-sleeve provided with an annular slot in its lower end, the lower wall of said slot provided with recesses therethrough, said brace-sleeve and 70 tube arranged for movement lengthwise of said stick independent of said rib-sleeve during which said hooks move through said recesses, and said hooks arranged by rotary movement thereof to be received in said 75 annular slot above said lower wall for connecting said sleeves for combined movement, substantially as described.

In testimony whereof, I have hereunto signed my name in the presence of two sub- 80 scribing witnesses.

NICHOLAS HIRTZ.
